UNITED STATES PATENT OFFICE.

PERCY FREDERICK BUTTERFIELD, OF TORONTO, ONTARIO, CANADA.

NAIL.

1,326,910.

Specification of Letters Patent.

Patented Jan. 6, 1920.

Application filed February 10, 1919. Serial No. 275,974.

To all whom it may concern:

Be it known that I, PERCY FREDERICK BUTTERFIELD, of the city of Toronto, in the county of York, in the Province of Ontario, 5 Canada, have invented certain new and useful Improvements in Nails, of which the following is the specification.

My invention relates to improvements in nails and the object of the invention is 10 to produce a nail which when driven, cannot withdraw out of wood by a direct longitudinal movement of the nail and will, therefore, permanently hold, the parts connected by the nail, together and which can 15 only be withdrawn by a turning movement of the nail during the pulling thereof and it consists essentially of the following arrangement and construction of parts as hereinafter more particularly explained.

Figure 1, is an enlarged perspective view 20 of my nail constructed in accordance with my invention.

Fig. 2, is a further enlarged cross sectional view through Fig. 1.

Fig. 3, is an enlarged perspective view of 25 a modified form.

Fig. 4, is a further enlarged sectional view through Fig. 3.

In the drawings like characters of reference indicate corresponding parts in the 30 various figures.

1 indicates a nail. 2, 3, 4 and 5 indicate spiral grooves extending longitudinally of the nail and arranged at a quarter turn 35 apart. The grooves 2, 3, 4 and 5 are of a low pitch corresponding to the pitch of the rifling of a rifle barrel. The grooves 2, 3, 4 and 5 are V-shaped in form and are provided at one side of each groove with a rib 40 6 extending outwardly from the surface of the nail, such rib terminating in a sharp edge. As the nail is driven the spiral rib 6 engages the wood and produces a turning movement of the nail as it is forced into 45 the wood, the portion of the wood compressed by the rib being forced into the groove and thereby forming, when the nail is driven, a complete key preventing the longitudinal movement of the nail.

In Figs. 3 and 4, I have shown an alternative form. In this form 7 indicates the nail. 8, 9, 10 and 11 indicate spiral grooves extending longitudinally of the nail and corresponding in form to the groove shown in Fig. 1. In this form, however, the groove 55 is provided with projecting ribs 12 and 13, which extend outwardly from the surface of the nail at each side of the groove. In both forms as indicated in Figs. 2 and 4 the inner face of the rib is formed by a continuation of the inner face of the corresponding side of the groove.

From this description it will be seen that I have devised a very simple device whereby a nail is absolutely prevented from withdrawing from the wood or other substance into which it is driven by a direct longitudinal movement and, therefore, securely fasten together the parts designed to be secured by the nail so that they cannot loosen 60 apart and yet will allow of an easy withdrawal of the nail by the hammer of the workman when the nail is given a spiral twist as it is withdrawn.

What I claim is my invention is.

1. A nail having a spiral groove extending longitudinally of the nail and having a rib extending outwardly from the surface of the nail at each edge of the groove.

2. A nail having a spiral groove extending longitudinally thereof V-shaped in form and having a sharpened rib extending from an edge of the groove, the inner face of the rib forming a continuation of the corresponding face of the groove.

3. A nail having a spiral groove extending longitudinally thereof V-shaped in form and having a sharpened rib extending from each edge of the groove, the inner face of each rib forming a continuation of the corresponding face of the groove.

PERCY FREDERICK BUTTERFIELD.
